[57] CLAIM

The ornamental design for dresser, as shown and de-
scribed.

DESCRIPTION

FIG. 1 is a perspective view of a dresser showing my
new design;

FIG. 2 is a side elevational view thereof;

FIG. 3 is a top plan view thereof; and,

FIG. 4 is a front elevational view thereof.

FIGS. 2, 3, and 4 have been drawn to a reduced scale in
respect to FIG. 1.

The undisclosed rear of the article is conventionally
plain and unadorned.
